UNITED STATES PATENT OFFICE.

MICHAEL L. GEHL, ARTHUR L. MERRIAM, AND HENRY M. GEHL, OF WEST BEND,
WISCONSIN.

MIXER.

1,340,947.

Specification of Letters Patent.

Patented May 25, 1920.

Application filed July 21, 1919. Serial No. 312,372.

To all whom it may concern:

Be it known that we, MICHAEL L. GEHL, ARTHUR L. MERRIAM and HENRY M. GEHL, all citizens of the United States, and residents of West Bend, in the county of Washington and State of Wisconsin, have invented certain new and useful Improvements in Mixers; and we do hereby declare that the following is a full, clear, and exact description thereof.

This invention refers to new and useful improvements to mixers of the centrifugal type, and more particularly to concrete mixers.

An efficient type of mixer of this character is one which may be tilted above an axis from loading and mixing position to dumping position, and which is rotatable in one direction when in the first mentioned position and rotatable in a reverse direction in the second position. In this way all the material mixed is effectively expelled from the mixing receptacle when the latter is in dumping position. All the mixers which have been devised to perform these functions, nearly all of them have been more or less complicated. It is therefore the principal object of this invention to provide a very simply constructed mixer which may be inexpensively manufactured and efficiently operated, and which will have all of the features which are considered essential in machines of this kind.

With this general object in view the invention resides in the novel features of construction, combination and arrangement of parts which will be hereinafter particularly described and claimed and shown in the drawing in which,

Figure 1 represents a side elevational view partly in section of the upper portion of a concrete mixer.

Fig. 2 is a plan view of the parts shown in Fig. 2, and

Fig. 3 is a detail sectional view taken substantially on the plane of the line 3—3 of Fig. 1.

This mixer consists essentially of a supporting frame, a mixing receptacle tiltably and rotatably mounted thereon, tilting means, and means for rotating the receptacle. The supporting frame only a small portion of which is depicted in the drawing, consists largely of angle metal bars, cer-

tain of which are arranged in inverted V-shape to form legs 1. The upper or apex ends of each pair of legs 1 are joined by a casting 2, the same having a leg attaching portion 3 and a bearing portion 4.

The mixing receptacle or drum 5 is of ordinary or conventional design, it having a stub supporting axle 6 projecting from its bottom in its longitudinal axis of rotation, the same being journaled in a bearing hub 60 forming part of the yoke 7. Each of the arms of the yoke has a laterally extending trunnion 8, said trunnions being journaled in open yoke-like bearings 9 formed in the bearing portion of the castings 2. Said 65 bearings being open the trunnions are readily seated therein between the upstanding arms which are connected by retaining pins or bolts 10 as shown in Figs. 1 and 2.

Disposed around the mixing drum adjacent the bottom thereof is a worm wheel 11, the teeth of which are adapted to mesh with the teeth of a worm 12 fixed midway the ends of a drive shaft 13 which is journaled in bearings carried by corresponding 70 legs 1. One end of this drive shaft is provided with power pulley 14 which may be driven in any desired manner.

The mixing drum both when in loading position and when in emptying position is disposed at an angle to the horizontal or vertical, the mouth thereof when in the first position being upwardly, while in the second position it is disposed downwardly to provide for ready removal of the contents. 85 From Fig. 1 it will be seen that the mixing receptacle is shown in one position in full lines and in the other position in dot and dash lines, and that when in both positions the teeth of the worm wheel 11 will be 90 meshed with the teeth of the worm 12, although while being moved to and from these positions said teeth will be disengaged. As a result of this the drum will readily be rotated in either of its two positions; the direction of rotation is, however, reversed in the two instances.

The teeth of the worm wheel 11 and the worm 12 are held in proper relation when in either loading or dumping position by 105 the engagement of a stop lug 15, carried by one of the trunnions 8, with either of two stop shoulders 16 and 17, both of which are formed on one of the castings 2. A handle 18 to which the stop lug 15 is attached, is 110

extended from said trunnion 8. This handle is used for tilting the mixing drum to shift the same from one position to the other, the stop lug 15 being engaged with the 5 stop shoulder 16 when the drum is in loading and mixing positions, whereas the stop lug engages the other shoulder 17 when maintenance of the mixing drum in dumping position is desired.

10 From the foregoing description it will be appreciated that we have devised an arrangement whereby a mixing receptacle, capable of being tilted from loading to dumping position, may be rotated in opposite directions when in its two positions, the rotation of the receptacle being discontinued, however, during movement of the same from one position to the other, this all being accomplished merely by the provision of a 15 single worm and a worm wheel having spiral teeth. The usual multiplicity of gears and gear rings together with other usual parts is thus eliminated. Various minor changes may be made in the form and proportion 20 and in the several details of construction without departing from or sacrificing any 25 of the features of the invention as herein before set forth.

We claim:

- 30 1. In a mixer, a supporting frame, a rotary mixing receptacle tilttable on said frame from loading to dumping position, a driven gear connected with the receptacle for revolving the same, a drive shaft journaled in the frame substantially parallel to the 35 tilting axis of the receptacle, a single driving gear on said shaft for intermittent engagement by the driven gear, and means for tilting the receptacle to swing the same 40 to and from said loading and dumping positions, said gears being engaged when the receptacle is in loading position and when in dumping position, and disengaged when the latter is being moved to and from either 45 of said positions.
2. In a mixer, a supporting frame, a rotary mixing receptacle tilttable on said frame from loading to dumping position, a worm wheel surrounding said receptacle, a drive shaft journaled in said frame and extended substantially parallel to the tilting axis 50

of the receptacle, a single worm on said drive shaft adapted to be intermittently engaged by said worm wheel, and means for tilting the receptacle to swing the same to 55 and from said loading and dumping positions, one portion of the worm wheel being engaged with the worm when the receptacle is in loading position to revolve the same in one direction, the worm being engaged 60 by another portion of the worm wheel when the receptacle is in dumping position to rotate the same in the reverse direction, said worm and worm wheel being out of engagement when the receptacle is being moved to 65 or from its loading and dumping positions.

3. In a mixer, a supporting frame comprising a pair of spaced end members, each having a bearing plate provided with a bearing, a rotatable mixing receptacle having 70 opposite extending trunnions seated in said bearings, a tilting handle fixed to one of the trunnions, a stop lug on the handle, a pair of stop shoulders on one bearing plate to be selectively engaged by the stop lug, and 75 means for revolving the receptacle when either stop shoulder is engaged by said stop lug.

4. In a mixer, a supporting frame comprising a pair of spaced end members, each 80 having a bearing plate provided with a bearing, a rotatable mixing receptacle having opposite extending trunnions seated in said bearings, a tilting handle fixed to one of the trunnions, a stop lug on the handle, a pair of 85 stop shoulders on one bearing plate to be selectively engaged by the stop lug, said stop shoulders being substantially 180° apart, a driven gear connected with the receptacle, and a driving gear to be engaged by the 90 driven gear to rotate the receptacle in one direction when said stop lug engages one stop shoulder and in the opposite direction when the other stop shoulder is so engaged.

In testimony that we claim the foregoing 95 we have hereunto set our hands at West Bend, in the county of Washington and State of Wisconsin.
